(57) **CLAIM**

The ornamental design for a pocket knife, as shown and described.

DESCRIPTION

FIG. 1 is a left, front perspective view of the pocket knife embodying the new design;

FIG. 2 right side elevation view of the pocket knife;

FIG. 3 is a left side elevation view of the pocket knife;

FIG. 4 is a top plan view of the pocket knife;

FIG. 5 is a bottom plan view of the pocket knife;

FIG. 6 is a front side elevation view of the pocket knife; and,

FIG. 7 is a rear side elevation view of the pocket knife.

The broken lines in the drawings represent portions of the pocket knife that form no part of the claimed design.
